(57) CLAIM

The ornamental design for a diaper changing table, as shown and described.

DESCRIPTION

FIG. 1 is a top, front and left side perspective view of a diaper changing table showing my new design;

FIG. 2 is a bottom, rear and right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and

FIG. 9 is an enlarged view of portion 9 in FIG. 1;

FIG. 10 is an enlarged view of portion 10 in FIG. 1;

FIG. 11 is an enlarged view of portion 11 in FIG. 1;

FIG. 12 is an enlarged view of portion 12 in FIG. 2;

FIG. 13 is an enlarged view of portion 13 in FIG. 2;

FIG. 14 is an enlarged view of portion 14 in FIG. 2; and,

FIG. 15 is an enlarged view of portion 15 in FIG. 2.

The evenly dashed broken lines illustrate portions of the diaper changing table and form no part of the claimed design. The unevenly dot-dash broken lines define the boundaries of the enlarged view and form no part of the claimed design.
